UNITED STATES PATENT OFFICE.

WHITMAN SYMMES, GEORGE H. HARMAN AND CHARLES F. DUVAL, OF SAN FRANCISCO, CALIFORNIA, ASSIGNEES TO THOMAS DAY COMPANY, OF SAN FRANCISCO, CALIFORNIA, A CORPORATION OF CALIFORNIA.

CHANDELIER.

Application filed June 9, 1926. Serial No. 114,688.

Our invention relates to chandeliers of the type employing removable translucent shades, and is particularly applicable to chandeliers which are pendant from the ceiling.

An object of our invention is to provide a chandelier in which a screen is used for preventing the source of light from being seen thru the open end of the shade, and for diffusing the light evenly over the surface of the shade.

Another object of our invention is to provide a chandelier in which the means for supporting the screen does not cast objectionable shadows.

Another object of our invention is to provide a chandelier in which the ceiling is directly illuminated.

Another object of our invention is to provide a chandelier in which the shade is readily removable but cannot be accidentally dislodged.

A further object of our invention is to provide a chandelier in which the screen is readily removable.

The invention possesses other advantageous features, some of which with the foregoing will be set forth at length in the following description where we shall outline in full that form of the chandelier of our invention which we have selected for illustration in the drawings accompanying and forming part of the present specification. In said drawings we have shown one form of chandelier embodying our invention, but it is to be understood that we do not limit ourselves to such form, since the invention as set forth in the claims, may be embodied in a plurality of forms.

In the drawings:

The figure is, on the left half, a sectional view of a chandelier embodying our invention and, on the right half, an elevation of the chandelier with a portion of the shade removed.

Various features of our invention which are disclosed in the accompanying drawing and are not claimed herein, are claimed in our co-pending application entitled "Lighting fixture" filed June 9, 1926, Serial No. 114,689.

Broadly speaking, our invention preferably comprises a chandelier provided with means for removably and adjustably sup-

porting a shade having an open end and provided with a screen to shield the source of light from view thru the open end of the shade, the screen being so supported that the shadow of the support falls on an opaque portion of the shade.

The chandelier of our invention is preferably suspended from the ceiling 3 by means of a chain 4 suitably supported in the ceiling and which is provided at the point of support with an ornamental cover 6. The lower end of the chain terminates in a tube 7 which may have external flutes to enhance its appearance and is threaded at its lower portion. The threads on the tube 7 are engaged by an electric socket 8 of the usual type provided with a light globe 9.

A translucent shade 11 is preferably placed about the light globe 9 and usually comprises a sheet of parchment or silk suitably fastened to a frame of any desired shape which is made up of a bottom rim 12, a top rim 13 and suitable spacing bars 14. In the present instance, the shade is approximately a circular cylinder. Means are provided for removably attaching the shade to the tube 7. These means preferably comprise a disc 17 which is held in place on the lower end of the tube 7 by a pair of jam nuts 18 and 19. The disc 17 is pierced to form a plurality of apertures. A corresponding number of radial arms 16 are fixed at their outer ends to the upper rim 13 and near their inner ends are bent to lie parallel with the tube 7. The ends of the arms 16 are bent over to form hooks which engage the disc 17 by means of the apertures therein. The supports for the shade can thus be readily lifted from the disc and the hook ends of the arms 16 can easily be inserted in the apertures again.

To prevent the hooked ends of the arms 16 from being accidentally dislodged from their seats within the apertures on the disc 17, a stop is provided to retain them in place. The stop preferably comprises a hood or ornamental husk 21 which is slidably mounted upon the tube 7 and is adapted to overlie the parallel portion of the arms 16 and to press the hooks into the apertures of the disc 17. The hood 21 is preferably forced down upon the hooked ends of the supporting arms 16 and is retained in place by a suitable collar 22 fastened to the tube 7 by means of a set

screw thereby clamping the entire assembly firmly in place. With the set screw loosened, the collar 22 can be pushed up the tube 7 and the hood 21 can be sufficiently raised to permit the hooked ends of the arms 16 to be disengaged from the disc 17.

A screen is preferably provided for shielding the source of light 23 from view below the shade 11 and for diffusing the rays of light evenly over the interior of the shade. The screen preferably comprises a bowl 24 of some non-transparent material such as suitably treated glass. The bowl or screen 24 is preferably supported by a metallic ring 26 which underlies a bead at the upper edge of the bowl. The ring 26 is in turn supported by a plurality of hangers 27 which are soldered or brazed to the ring 26 and are hooked at their upper ends to engage the radial supporting arms 16. The length of the hangers 27 and the size of the bowl 24 is preferably made such that the opaque supporting ring 26 is in alignment with the opaque rim 13 of the shade and the source of light 23. By having those parts in alignment, the shadow cast by the ring 26 falls upon the rim 13 and does not produce a shadow upon the shade 11 where it is highly undesirable. The parts are proportioned and assembled to produce approximately this result and the final adjustment may be made by manipulating the jam nuts 18 and 19 thereby raising or lowering the disc 17 and correspondingly raising or lowering the shade 11 and the bowl 24 to provide an exact alignment with the source of light 23. The bowl 24 prevents the source of light from being visible from below the shade and also diffuses the light evenly over the interior of the shade 11, at the same time permitting light rays to radiate directly to the ceiling. The bowl 24 may readily be removed for replacement of the globe 9, or for cleaning

simply by raising the ring 26 slightly, giving a twist to the ring and then lowering it, the twist being sufficient to disengage the hooked ends of the hangers 27 from the supporting arms 16.

We claim:

1. A chandelier comprising a tube, a source of light supported by said tube, a disc mounted on said tube, said disc having apertures therein, a plurality of radially extending supporting arms having portions extending parallel to said tube and hooking over said disc into said apertures, a hood mounted on said tube and overlying said supporting arms for retaining said supporting arms in place, a substantially cylindrical shade supported by said supporting arms, an opaque rim on the upper edge of said shade, a plurality of hangers depending from said supporting arms, an opaque ring supported by said hangers whereby shadows of said ring fall substantially entirely on said rim, and a non-transparent bowl depending from said ring.

2. A lighting fixture comprising a cylindrical translucent shade open at the top and bottom, a lamp arranged within the shade, a translucent bowl, interposed between the lamp and the shade and arranged to prevent direct passage of rays of light from the lamp to the shade and to permit direct passage of rays of light from the lamp through the whole open top of the shade, and a ring on which said bowl is supported, said ring being positioned so that the shadow of the ring falls substantially along the upper edge of the shade.

In testimony whereof, we have hereunto set our hands.

WHITMAN SYMMES,
GEORGE H. HARMAN,
CHARLES F. DUVAL.
